UNITED STATES PATENT OFFICE.

ALBERT BROADMEYER, OF HARRISBURG, PENNSYLVANIA, ASSIGNOR TO THE W. O. HICKOK MANUFACTURING CO., OF HARRISBURG, PENNSYLVANIA, A CORPORATION OF PENNSYLVANIA.

PAPER-FEEDING MACHINE.

1,183,626.

Specification of Letters Patent. Patented May 16, 1916.

Application filed May 20, 1915. Serial No. 29,326.

To all whom it may concern:

Be it known that I, ALBERT BROADMEYER, a subject of the Emperor of Germany, and a resident of Harrisburg, in the county of 5 Dauphin and State of Pennsylvania, United States of America, have invented a certain new and useful Improvement in Paper-Feeding Machines, of which the following is a specification.

10 This invention relates generally to paper feeding machines, and more particularly to automatic machines of this character for use in connection with ruling machines, the primary object thereof being to provide a 15 feeding machine operable in timed relation from a ruling machine to feed sheets continuously, or at proper intervals thereto, and which will be highly effective for this purpose, strong and durable in use.

20 More specifically, the invention aims to provide a vertically adjustable feed table on which the paper sheets are stacked, together with means operable in connection with thick and thin, rough and even paper, whereby to 25 elevate the table automatically and in step by step movements, as paper is fed therefrom, in order to maintain the top of the stack in practically the same position at all times.

30 The invention further aims to provide automatic means whereby to withdraw sheets from the stack and transport the same to the ruling machine, without injury, and without regard to the particular condition of 35 the paper, that is, whether thick, thin, rough, or smooth.

The invention further aims to provide air connections whereby the successful feed of the paper may be accomplished, together 40 with means automatically controlling such air connections from the operating parts of the ruling machine.

45 Other and still further objects of this invention, including means to prevent the feed of two or more sheets at a time, together with the advantages resulting therefrom, will appear more clearly from the following description, in which reference is made to the accompanying drawings forming a part of this specification, and in which—

Figure 1 is a plan view. Fig. 2 is a side

elevation. Fig. 3 is an enlarged side elevation of that part of the feeding machine adjacent to the feed table and looking at the 55 relatively opposite side thereof as compared to Fig. 2. Fig. 4 is a detail vertical longitudinal section taken therethrough substantially on line 4—4 of Fig. 1. Fig. 5 is a vertical cross section, enlarged, taken substantially on line 5—5 of Fig. 1. Fig. 6 is a similar view, taken substantially on line 6—6 of Fig. 1. Fig. 7 is another similar view taken substantially on line 7—7 of Fig. 1. Fig. 8 is a detail vertical section taken 65 on line 8—8 of Fig. 6. Fig. 9 is a similar view taken on line 9—9 of Fig. 6. Fig. 10 is still another similar view taken on line 10—10 of Fig. 6. Fig. 11 is a view partly in side elevation and partly broken away and 70 in section showing the clutch at one end of the shaft of the roller shown in Fig. 7. Fig. 12 is a vertical section taken substantially on line 12—12 of Fig. 11. Fig. 13 is a view in elevation of part of the clutch shown in Fig. 75 11, with the parts in unclutched position. Fig. 14 is a vertical section taken substantially on line 14—14 of Fig. 11. Fig. 15 is a diagrammatic perspective view illustrating the air connections, particularly the blast 80 connections for agitating the paper in the stack. Fig. 16 is a detail vertical section taken substantially on line 16—16 of Fig. 15. Fig. 17 is a detail section taken substantially on line 17—17 of Fig. 16. Fig. 18 is a vertical longitudinal section through one of the air valves taken substantially on line 18—18 of Fig. 19. Fig. 19 is a cross section taken 85 vertically through one of the valves, substantially on line 19—19 of Fig. 15. Fig. 20 is a similar view through another of the valves, taken substantially on line 20—20 of Fig. 15. Fig. 21 is another similar view taken through still another valve substantially on line 21—21 of Fig. 15. Fig. 22 is 90 a detail side elevation of a portion of the machine, illustrating the automatic means whereby to prevent the feed of two or more sheets at a time. Fig. 23 is a detail vertical section taken substantially on line 23—23 of 100 Fig. 22. Fig. 24 is a detail elevation illustrating the cam and controlling connection of one of the air valves shown in Fig. 15. Fig. 25 is a detail horizontal section taken

substantially on line 25—25 of Fig. 24. Fig. 26 is a detail perspective view of certain of the parts plainly shown in Fig. 3. Fig. 27 is a detail vertical section taken substantially on line 27—27 of Fig. 3. Fig. 28 is a perspective view looking from the base of a portion of the feed table seen in Fig. 5. Fig. 29 is an enlarged detail section of certain of the parts shown in Fig. 5, and to be 10 more specifically referred to hereinafter. Fig. 30 is a detail vertical section through one of the paper stack engaging members. Fig. 31 is a similar view of another paper engaging member. Fig. 32 is a detail perspective view illustrating the clutch connection between the table controlling shaft and its crank. Fig. 33 is a diagrammatic view illustrating the electrical connection for controlling the vertical adjustment of the feed 20 table and for use in connection with rough and uneven paper. Fig. 34 is a detail vertical section through certain parts of the apparatus shown in Fig. 33 and taken substantially on line 34—34 of said figure, and Fig. 25 35 is an end view of the paper stack shown in Fig. 33.

Referring now to Figs. 1 and 2, it will be seen that at the rear of the feeding machine is arranged a frame in which the feed table 30 is vertically adjustably disposed, this frame consisting of a base 50 from which a pair of standards 51 rise at each side, the upper ends of these standards supporting upper side frames 52, rigidly connected and spaced 35 apart by transverse tie rods 53 and 54 as best seen in Figs. 4 and 5.

By referring to Fig. 5 it will be noted that the upper side frames 52 have journals for the upper ends 55 of screw bars 56, disposed between the standards 51 at each side of the feed table frame, the upper extremities of which screw bars are provided with fixed bevel gears 57 in mesh with similarly fixed bevel gears 58 of a transverse shaft 45 59 journaled at its ends through the upper portions of the upper side frames 52, it being also seen in Fig. 5, that one projecting end of the shaft 59, at the right hand side of the machine and looking forward, as will 50 be seen by reference to Fig. 1, is provided with a ratchet wheel 60, rigidly secured thereto, and having at one side a clutch face 61 with which the clutch socket 62 of a crank 63 is engageable, the crank itself being longitudinally adjustable upon one extremity 55 of the shaft 59 to engage with and disengage from the clutch face 61 just mentioned. The relatively engageable clutch faces 61 and socket 62, the latter carried by the handle 63, will be plainly seen by reference to the detail Fig. 32.

At each side of the feed table frame thus formed, is arranged a longitudinally extending bracket 64, having end yokes 65,

see Fig. 2, engageable with the standards 51 65 in sliding relation, and having a central threaded bearing 66 through which the respective screw bar 56 extends, whereby upon rotation of the screw bars 56, the supporting brackets 64 will be raised and lowered, dependent upon the direction of such rotation. It will be noted that each of the supporting brackets 64 has upwardly projecting studs 67, one of which is plainly seen in Fig. 5, which are adapted to be received in conformable recesses in the lower surfaces of side cleats 68 secured to the under side of the feed table 69, whereby the latter may be disposed in proper relation with respect to the supporting brackets 64 by registering 70 the recesses of its cleats 68 with the studs 67 just before mentioned.

By referring to Figs. 1, 5, and 28, it will be seen that the feed table 69 is provided at one side with inwardly projecting transversely extending slots 70 in which plates 71, seen in Fig. 28, are disposed, each of these plates 71 being provided with a clamping block 72 by which the same may be secured in selected adjustment within the slots 70 by a clamping bolt 73 seen in Fig. 5, each of said adjusting plates 71 also carrying a depending socket 74 adapted to receive the lower end of one of the upright paper guide rods 75, of which there are two at one side 95 of the paper stack 76, this stack being guided at its opposite side by means of a guide plate 77 as seen in Figs. 1 and 4, supported at the lower end of an arm 78, the upper end of which is adjustably connected 100 by a wing nut 79 to a clamp 80, rigidly attachable to the tie rod 54 as plainly seen in Fig. 4. The plates 71 may be connected by a bar 71^a. Being thus located in proper position between the guide rods 75 and the 105 guide plate 77, the paper stack is moved forwardly against the upper end of spaced rigid upright guide strips 81 as plainly seen by reference to Fig. 15, this position shown in Fig. 1, being the normal position of the 110 stack ready for operation, although it is to be understood that the rods 75 and the guide plate 77 are laterally adjustable with respect to the feed table in order to accommodate a desired width of paper. With the 115 paper stack thus disposed in proper position, and elevated through the use of the hand crank 63 of the controlling shaft 59, the sheets are removed one at a time and fed forwardly by the action of a suction cylinder 82 journaled transversely above the forward edge of the feed table and immediately above the upper end of the forward spaced upright paper guide strips 81 before mentioned, the relative arrangement of this suction cylinder 82 being readily seen by reference to Figs. 1, 2, and 4. 120 In order to effect automatic vertical ad-

justment of the feed table 69, the controlling shaft 59 is provided upon its projecting end with a loosely disposed weighted arm 83, best seen in Fig. 3, and the weight of which 5 normally tends to force the same downwardly and rearwardly, this weighted arm being provided with pivoted spring controlled pawls 84 at points diametrically opposed to one another with respect to the 10 ratchet wheel 60, the sides of which they engage. The lower end of the weighted arm 83 is provided with a pivoted contact finger 85 which, by reference to Fig. 26, will be seen to have a slight rearward movement 15 under control of a spring 86, and to be prevented from forward movement by a stop pin 87. This contact finger 85 normally engages the teeth of a curved rack 88 at the forward portion of a horizontally extending 20 latch 89, the rear end of which is pivotally mounted at 90 upon a stud 91 projecting from the adjacent upper side frame 52, and having a rearwardly projecting balancing arm 92 extending rearwardly beyond its 25 pivot 90 and provided with an adjustable weight 93, as shown in Fig. 3.

At an intermediate point 94 of the latch 89 is pivotally connected the rear end of an arm 95 rigidly connected at its forward end 30 to one end of a cross rod 96 which, as plainly seen in Fig. 1, is journaled transversely between the forward portions of the upper side frame and is provided intermediate its ends with a controlling rod adjustably clamped 35 thereto by a clamp 98, the said controlling rod 97 extending rearwardly above the paper stack 76 and carrying an adjustable element 99 which engages the top of the paper stack itself. This paper engaging element 99 may either have a lower paper engaging roller 100 as seen by reference to Figs. 3 and 30, or may carry a depending rigid paper engaging pin 101 as shown in connection with the element 102 as seen in 40 Fig. 31, the element 99 in Fig. 30 being utilized with thick paper and the element 102 shown in Fig. 32, being used with thin paper. Thus during the use of the machine, as successive layers of the paper are fed 45 from the top of the stack 76 by the action of the suction cylinder 82, the lowering movement of the paper engaging element 99 permits the rear end of the controlling rod 97 to lower, thus rocking the cross rod 96 50 and swinging the rear end of its arm 95 downwardly, the result of which is to slightly lower the forward end of the latch 89 upon its rear pivot 90, to permit swinging movement of the weighted arm 83 before 55 mentioned, and as shown in dotted lines in Fig. 3, during which movement the pawls 84 slide over the teeth of the ratchet wheel 60. The lower portion of the weighted arm 83 however, is provided with a laterally and

outwardly projecting pin 103 disposed in a 65 longitudinal slot 104 at the rear end of a connecting rod 105, the forward end of which is connected to the wrist pin 106 of a crank 107 the latter being connected to one end of the suction cylinder 82 in a manner to be hereinafter described.

The slot 104 is of substantially the length of the curved and inclined rack 88 of the latch 89 and, during constant rotation of the suction cylinder 82, the connecting rod 75 105 is continuously reciprocated so that whenever the weighted arm 83 is permitted swinging movement, during which the pawls 84 slide over the ratchet wheel teeth as before described, the action of the connecting 80 rod 105 immediately returns the weighted arm 83 to its normal position shown in full lines in Fig. 3 and thus restores the automatic controlling parts to their original position. During the return movement of the 85 weighted arm 83 the engagement of the pawls 84 with the teeth of the ratchet wheel 60 cause a slight rotation of this ratchet wheel, and a similar rotative movement of the controlling shaft 59, which movement is 90 communicated through the bevel gears 58 and 57 to the screw bars 56, rotation of which elevates the feed table 69 through the side brackets 64 connected as before described.

By referring to Figs. 5 and 29, it will be noted that the shaft 59 before referred to, is provided adjacent one end, and between the upper side frames 52, with a loose pulley 108 having an annular flange 109 provided in its outer face with an aperture 110, this aperture being adapted for the reception of a clutch pin 111 carried by an annular clutch plate 112 securely fastened to the shaft 59 at 113. This clutch pin 111 is 100 normally held in inoperative withdrawn position as shown in Fig. 5 during the operation of the machine. When the stack of sheets 76 is exhausted or nearly so, however, the clutch pin 111 may be thrown in, 105 thus coupling the loose pulley 108 to the shaft 59, the operator at the same time withdrawing the pawls 84 from the ratchet wheel 60. Around the pulley 108 is extended the rear end of a belt 114, the forward end of which belt as plainly seen in Fig. 1, is extended around one end portion of the suction cylinder 82, see also Fig. 6, so that, when the pulley 108 is clutched, the rotation of the suction cylinder 82 is communicated to the shaft 59, rotating the same to similarly rotate the screw bars 56 and lower the table 69.

From Fig. 5 and also from Fig. 2, it will be noted that one of the bearings 66 of the adjacent side bracket 64 is provided with an extended bearing or tubular piece 115 loosely through which extends a vertical

rod 116 having an adjustable set collar 117 secured thereon below the said side bracket, and with which the extended portion 115 just mentioned comes into engagement as shown in dotted lines in Fig. 5, when the table is lowered through the action of the belt 114, thus causing lowering movement of the rod 116, the upper end of which is secured to a flexible connection 118 passing over a pulley 119 supported upon the adjacent upper side frame 52 and connected at its forward end to a clutch operating member for disengaging a clutch in the driving connections to the suction cylinder 82 as hereinafter described, when the table 69 has been thus lowered.

The automatic means before described for elevating the table 69 in step by step movement during the usual operation of this machine, are well adapted to serve the intended functions in connection with either rough or smooth paper which is even and regular. Where uneven or irregular paper is encountered, however, I preferably use a modified form of actuating mechanism shown in Figs. 33, 34, and 35.

Referring now to Fig. 33 which is more or less diagrammatic in form, I have shown the contact piece 85^a of the weighted arm 83^a, which carries the pawls 84^a in engagement with the ratchet wheel 60^a, as normally held by the shouldered end 120 of a lever 121 intermediately fulcrumed at 122 and having a rearwardly projecting arm 123 provided with an adjustable weight 124 counterbalancing the same, the end 120 of this lever constituting an armature and being disposed adjacent to electro-magnets 125. A battery 126 is in circuit with the electro-magnets 125 through circuit wires 127 and 128, the latter of which includes a mechanical switch 129. The circuit wires 127 and 128 respectively lead to a rigid arm 130 and one end 131 of an intermediately pivoted lever 132, the opposite end of which lever is provided with a vertically adjustable paper engaging element 133 normally disposed upon the rear central portion of the paper stack 76^a as shown in both Figs. 33 and 35, the said rigid arm 130 and the said end 131 of the lever 132 being provided with registering contact pins 134 and 135 respectively, which upon lowering movement of the rear end of lever 132, come into engagement and complete the circuit through the electro-magnets 125 which attract the armature 120 and thus release the contact piece 85^a of the weighted arm 83^a which is thus free to move downwardly and rearwardly by gravity and is returned in order to raise the paper holding table by connections 105^a corresponding to the connections 105 previously described. There is also shown in Fig. 33 a

pair of rods 53^a and 54^a, and a shaft 59^a, 65 corresponding to the tie rods 53 and 54 and the shaft 59 of the figures before described, it being noted that in the automatic mechanism illustrated in Fig. 3, a frame 136 is clamped, by a clamp 137, to the rod 53^a, this frame having a lower horizontally slotted portion 138 adjustably carrying an insulated support 139 above the paper stack 76^a, by means of a clamp 140, this insulated support 139 carrying the rigid arm 130 and the lever 132 before mentioned, which connections together with the clamp 140 will be better seen by reference to Fig. 34. There is also shown in Fig. 33 a cross rod 96^a corresponding to the cross rod 96 in the figures 80 before mentioned, to which rod 96^a are loosely connected the forward ends of rearwardly projecting rods 141 disposed upon opposite sides of the lever 132 and having adjustable paper engaging members 142 85 adjacent their rear ends, the function of which is to press downwardly upon the paper stack 76^a due to the weight of the rods 41 and assist in maintaining the rough uneven stack 76^a as flat as possible. 90

Referring now to the suction cylinder 82 as shown in detail in Fig. 6, it will be noted that this cylinder consists of two cylindrical sections 143 and 144, their inner ends being joined by a threaded connection 145 and it 95 will be further noted that this suction cylinder is provided with an intermediate section, approximately one third of its length, provided with a plurality of minute apertures 146. Suction cylinder 82 is also provided with reduced ends 147 and 148, carried respectively by its sections 143 and 144, and is surmounted by a pair of sleeves 149 and 150, which sleeves are movable toward and away from one another to regulate the 100 effective area of the intermediate apertured portion of the said cylinder for a purpose to be hereinafter described.

The reduced end 148 of the suction cylinder 82 extends through a rigid bearing 151 110 and is rigidly attached to the crank 107 before described, by means of a setscrew 152, this crank 107 having an inner annular recess 153 in which a block 154 is rotatably seated, this block having a rectangular slot 115 155 as shown in the detail Fig. 10, receiving the squared outer reduced end 156 of a supporting rod 157, extending substantially along the longitudinal axis of the cylinder 82 through its section 144. 120

The opposite reduced end 147 of the cylinder 82, around a portion of which the belt 114, before mentioned, is extended, projects through a bearing 158, adjacent to which bearing is a rigid bracket 159 having a rectangular slot 160 in which is disposed a similar shaped block 161 to which the outer end portion of a suction tube 162 is secured, 125

this suction tube 162 extending inwardly along the longitudinal axis of the section 143 of the suction cylinder 82 and thus in a plane coincident with the supporting rod 5 157 before mentioned.

The inner ends of the supporting rod 157 and the suction tube 162, which rod and tube are thus supported in non-rotative relation free to move up and down, are connected to 10 and support the relatively opposite ends of a suction nozzle or mouthpiece 163, the lower curved wall 164 of which mouthpiece closely engages the lower portion of the suction cylinder 82 and is in length substantially 15 the length of the apertured area of said suction cylinder, all of which will be plainly seen by a comparison of Figs. 4 and 6.

The suction mouthpiece 163 being thus of its own weight adapted to maintain its lower 20 curved wall 164 in close contact with the lower inner surface of the suction cylinder 82, which lower wall is provided with a longitudinally extending slot 165, is thus well adapted to create suction through the several 25 openings 146 of the suction cylinder as they arrive below the slot 165 during the rotation of the suction cylinder 82 which is continuous in the operation of the machine, the result being to suck upwardly against the lower periphery of the cylinder 82, the forward end of the uppermost sheet of the stack 76 as plainly indicated in Fig. 4, such sheet upon being so sucked up against the cylinder being then fed forwardly as the 30 cylinder 82 rotates, its forward edge being moved onto a series of traveling tapes 166, the rear ends of which extend over a wooden roller 167 journaled transversely across the machine forwardly of and below the suction 35 cylinder 82 as plainly seen in Fig. 4.

Referring again to Fig. 6, it will be noted that the reduced end portion 147 of the suction cylinder 82, is provided with a pair of gears 168 and 169, the former being of substantially 45 greater size than the latter, these two gears being integrally formed and in respective connection with separate, small and large gears 170 and 171 of the shaft 172 of the wooden roller 167 before referred to, 50 through intermediate gears 173 plainly seen in Figs. 6 and 8.

Referring now to Fig. 7, the shaft 172 of the wooden roller 167 extends through bearings 174 and 175 at its relatively opposite ends, its gears 170 and 171 before mentioned, being loose thereon and each provided with an aperture 176. Adjacent each of the gears 170 and 171 is a rigid clutch plate 177 having a pin 178 for engagement in the aperture 176 of its respective gear 170 and 171. Thus, when the gear 170 is clutched, a relatively slow speed is imparted to the suction cylinder 82, whereas when the gear 171 is clutched, a relatively increased speed is im-

parted to the suction cylinder, control of 65 the speed of which is desirable in order that the paper sheets may be fed fast or slow depending upon the character of work performed in the ruling machine to which the paper sheets are fed. The sheets of paper 70 thus delivered by the action of the continuously rotating suction cylinder 82 upon the tapes 166, the rear ends of which pass around the wooden roller 167, and the forward ends of which pass around a roller 179, 75 as seen in Fig. 1, and carried forwardly by said tapes in their movement, between side paper guides 180 and 181, parallel with the side frame bars 182 and 183, are delivered between superposed rollers 184 at the rear 80 of the ruling machine, the rear portion of the frame 185 of which is clearly shown in Figs. 1 and 2, the rollers 184 receiving the paper, having interengaging gears 186 and 187 at their outer ends, the latter of which 85 is driven through a suitable gear train, from a suitable source of power, and one gear of which train is indicated at 188 in Fig. 2. The gear 187 is also provided with a sprocket wheel 189 and from this sprocket 90 wheel, a sprocket chain 190 extends longitudinally along and outside of the frame side bar 183 as will be clearly seen by reference to Fig. 1, with its rear end around a sprocket wheel 191 loosely disposed upon 95 one projecting end of the shaft 172 of the wooden roller 167 before mentioned. This sprocket wheel 191 is connected to the shaft 172 of the wooden roller 167 by means of an automatic clutch to be now described, as 100 particularly shown in Figs. 11 to 14 inclusive.

Referring now to Fig. 11, it will be seen that the sprocket wheel 191 is rigidly attached by machine bolts 192, to the outer 105 side of an annular disk 193 also loose upon the shaft 172, this disk carrying a pair of spring controlled pawls 194 normally in engagement with the teeth of a ratchet wheel 195 secured upon the shaft 172 as 110 clearly seen in Fig. 12, pawls 194 having laterally and inwardly projecting pins 196 adapted for engagement by the annular bevelled face 197 of a clutch controlling member 198 longitudinally shiftable with respect to 115 the shaft 172 and having at its inner end a cam shoulder 199 normally disposed within a conformable recess 200 at the outer end of a sleeve 201 disposed on the shaft 172 and held against rotation by means of pins 202 120 rigid therewith and entering recesses in the adjacent bearings 174 of the shaft 172 as plainly seen in Figs. 7 and 11, the relatively engaging cam shoulder 199 and recess 200 being plainly seen in Fig. 13. Thus rotative 125 movement of the clutch controlling member 198 in either direction serves to shift the same longitudinally of the shaft 172 and

toward the ratchet wheel 195, the result being that its conical face 197 engages the pins 196 of the pawls 194 so as to shift the pawls on their pivots away from, and out of engagement with ratchet wheel 195 before mentioned. To this end, the clutch controlling member 198 has an upright rigid arm 203 to which the forward end of the flexible connection 118 is secured, the rear end of which connection is secured to the vertically shiftable rod 116. To the upright arm 203 is also connected the rear end of a connecting rod 204, extending forwardly along the machine and connected at its forward end to a cam disk 205, as will be plainly seen by reference to Figs. 1, 2, and 22. Referring now particularly to Fig. 22, it will be noted that the connection of the forward end of the actuating rod 204 is above the fulcrum 206 of the cam disk 205 upon the outer face of the frame side bar 183, and that to this cam disk 205 the upper end of a retractile spring 207 is connected at a point forwardly of the fulcrum 206, the lower end of said spring being anchored in the lower portion of a vertically adjustable bracket 208 as best seen in Fig. 23, which is held in adjusted position in connection with the frame side bar 183 by a set screw 209. The upper portion of the cam disk 205 is provided with a forwardly presented shoulder 210 engaged by the lower end of a threaded pin 211 adjustably mounted through the forward end of an arm 212, the rear end of which is securely fastened to a cross shaft 213, above and forwardly beyond, the wooden roller 167 before mentioned, so that the cam disk 205 is normally held in its inactive position as best seen in Fig. 23. The shaft 213 just mentioned extends transversely above the series of tapes 166, its ends projecting through upright bearings 214 attached to the side frame bars 183 as best seen by reference to Figs. 1 and 22, and is provided with forwardly and rearwardly projecting arms 215 and 216 respectively, the latter arm being loosely connected to the shaft 213 to swing freely in a vertical direction thereon, and having at its rear bifurcated end a roller 217 bearing upon the wooden roller 167 as shown in Fig. 7, and acting to press the paper downwardly into engagement with the tapes 166 and thus promote a steady uniform movement of the paper so fed.

The forwardly projecting arm 215 is rigidly connected at its rear end to the said shaft 213, and is provided at its forward end with a roller 218 as plainly seen in Figs. 1 and 22, which roller bears downwardly upon a companion roller 219 mounted upon a lower transverse shaft 220, extending between the side frame bars 182 and 183 below the upper run of the tape 166, this latter shaft 220

being provided at one side with a sprocket 65 wheel 221 connected by a sprocket chain 222 with a sprocket wheel 223 secured to one end of the wooden roller 167 as seen in Fig. 7, the shaft 220 being thus driven from the wooden roller 167. The roller 219 of the 70 shaft 220 projects upwardly to substantially the level of the upper runs of the tapes 166 and the arm 215 being rigid with the shaft 213, upward movement of arm 215 under the pressure of the sheet of paper 75 passing beneath the roller 218, serves to raise arm 215 and thus oscillate the shaft 213 to a limited extent which is permitted by adjustment of the vertical pins 211 before mentioned and controlling the cam plate 80 205. When, however, two sheets are fed at the same time upon the tapes 166, the increased thickness of the material so fed causes upward movement of the arm 215, oscillating shaft 213 to such an extent that 85 the vertical movement of the pin 211, in consideration of the fact that the arm 212 is of greatly increased length with respect to the arm 215, elevates the pin 211 out of contact with the shoulder 210 of the cam plate 90 205, which cam plate is thereupon rocked upon its fulcrum 206 by the action of the spring 207 so as to move rod 204 forwardly to oscillate the clutch controlling member 95 198 with which rod 204 is connected as before described, thus releasing the clutch through the action of the parts thereof as previously described.

Forwardly of the cam piece 205 is a transverse shaft 224 journaled through the side 100 frame bars 182 and 183, and provided at one side adjacent to the cam plate 205 and beneath its forward extension 225, with a rearwardly projecting crank 226 having a roller 227 which, upon oscillatory movement 105 of shaft 224, is adapted to engage upwardly beneath the forward extension 225 of the cam plate 205 and elevate said cam plate to its normal locked position as shown in Fig. 22, after automatic release thereof due to 110 the attempted passage of two or more sheets at the same time along the tapes 166, the relatively opposite end of shaft 224 having a handle 228 adjacent the forward end of 115 this machine and therefore adjacent the operator's station indicated by the arrow A in Fig. 1.

Referring now to Figs. 2 and 15, it will be seen from the former of these two figures, that an air pump of suitable character is 120 shown at 229 below the frame consisting of the side bars 182 and 183, this pump being connected to suction and blast pipes 230 and 231 by flexible connections 232 and 233 respectively, said suction and blast pipes 230 125 and 231 being mounted transversely across the machine and forwardly of the upright forward paper guides 81, in brackets 234

attached to certain of the said guides, as plainly indicated in Fig. 15. Adjacent one end the suction and blast pipes 230 and 231 are provided with slots 235 and 236 respectively and are surmounted adjacent said slots by slotted valve sleeves 237 and 238, the slots 239 and 240 of which sleeves are adapted to register more or less with the respective slots 235 and 236 of the suction and blast pipes, in order to control the operative force of the suction and blast respectively from the pump 229. The detail structure of these air valves 237 and 238 will be better seen by reference to Figs. 20 and 21 respectively cross sections therethrough each of the valves being under control of the operator of the machine, and to this end the suction pipe valve 237 which is required to be more frequently adjusted, is provided with diametrically extending arms 241 connected by rods 242 to a controlling lever 243 mounted adjacent the operator's station as will be seen by reference to Fig. 1. At its relatively opposite end, the suction pipe 230 is connected, by an upright flexible connection 244, to the outer end of the suction tube 162 extending through the reduced end 147 of the suction cylinder 82, and adjacent the connection 244 just described, the suction pipe 230 is also provided with a slot 245 and is surmounted by a rotary valve sleeve 246, constituting a cut-off valve and having a slot 247 adapted to register with the slot 245 of the suction pipe as better seen in Fig. 19. This valve sleeve is also provided with an upright arm 248 connected by a forwardly extending rod 249, extending through a portion of the frame 185 of the ruling machine as clearly seen by reference to Figs. 2 and 24, the forward extremity of rod 249 being pivotally united at 250 to the lower end of a lever 251 pivoted at its upper end at 252 to a portion of the frame 185 of the ruling machine, and acted upon by a cam 253, in order to periodically move the valve 246 to fully register its aperture with the aperture 245 of the suction pipe, thus destroying entirely the effect of the suction and arresting the action of the suction cylinder 82.

Referring to Fig. 24, it will be seen that rearwardly of the frame 185 of the ruling machine, the connecting rod 249 is provided with an adjustable set collar 254 and is surrounded by a coiled spring 255 extending between the said set collar and the frame 185 of the ruling machine and the action of which is to normally create a rearward tension upon the rod 249 to maintain the valve 246 closed.

The cam 253, as best seen by reference to Fig. 25, is adjustably clamped upon a sleeve 256 and in connection with a gear 257, the sleeve 256, with the gear 257 and cam 253,

and also with the wing nut 258 by means of which these parts are adjustably clamped, being loosely disposed upon the projecting portion of a rigid stud 259, and the gear 257 receiving its rotation through a train of gears 260, 261, and 262, the latter of which meshes with the before mentioned gear 187, and of which train of gears, gear 262 is adjustably and removably supported upon a bracket 263 by means of a clamp 264. Thus the speed of rotation of the cam 253, as well as its relative position, may be readily adjusted so as to cut off the valve 246, and the action of the suction cylinder 82, at just the proper time with respect to the movement of the parts of the ruling machine. 80

Adjacent its opposite ends, the blast pipe 231 as plainly seen in Fig. 15, is connected by flexible connections 265 to the relatively opposite end of an upper blast tube 266, tube 266 being extended through a concentric tube 267 and provided with a longitudinal slot 268 as best seen by reference to Figs. 16 and 17. The concentric tube 267 is also provided with a series of relatively short longitudinal slots spirally arranged there-around, and this tube may be rotated on the tube 266 in order to bring any one of the series of slots 269 thereof in registry with the slot 268 of the inner tube 266 for a purpose to be now described. 95

The tubes 266 and 267 are supported in vertically adjustable relation by means of brackets 270 secured to certain of the upright paper guides 81, as clearly seen in Fig. 15, and to which the said tubes are connected by means of adjustable screw rods 271, and the outer tube 267 is provided with curved nozzles slidably disposed thereon, the nozzles being indicated at 272 and having set screws 273 whereby they may be secured in adjusted position, these nozzles being projectable either above or below the tube 267, both of which positions are indicated in Fig. 15, and having as their functions the delivering of air blasts against the forward edge of the paper stack 76 in order to agitate the forward edges of the paper and enable the suction cylinder 82 to readily lift the top sheet from the stack for the purposes before described. 115

Thus from the foregoing description of the construction and operation of the several parts of this machine, it is believed that its operation as a whole may be readily understood. It is to be noted, however, that in addition to the automatic release of the clutch shown in Figs. 11 to 14 inclusive by the passage of two or more sheets beneath the roller 218, the operator may release these parts by the operation of a handle 274 carried by the end of the shaft 213 opposite to that to which the arm 212 is connected, as best seen in Fig. 1. The operator at his 120 125

station A may thus regulate the effective force of the suction communicated through the suction cylinder 82, by manipulation of the valve controlling lever 243, and he may 5 release the normally locked cam disk 205 by manipulating handle 274 of shaft 213, in addition to resetting the cam disk 205 by manipulation of the handle 228 of the resetting shaft 224.

10 It is also to be understood that when the table 69 is to be lowered, the operator pulls the pawls 84 out of engagement with the ratchet wheel 68 and clutches the pulley 108 by releasing the pin 111 and moving the 15 same into the flange aperture 110, the table being thereby lowered through the action of belt 114 from the suction cylinder 82. As before described, when the table has been lowered until it engages the set collar 117, thereby lowering rod 116, the clutch is withdrawn by rearward oscillating movement of the clutch operating member 198, thus disrupting the driving connections to the several feeding parts of the machine. When 20 a new supply of paper sheets has been furnished, the table is then elevated to the proper position as best seen by reference to 25 Fig. 4, by the hand crank 63.

It will be understood that a machine so 30 constructed will be light in weight, practical and efficient in its operation, and strong and durable in use, and that the feeding parts may be controlled through the adjustment of the driving connections best shown 35 in Fig. 2 from the ruling machine, so as to accurately and minutely adjust and time the feeding operation in accordance with the movement of the operating parts of the ruling machine itself, sheets being fed either 40 at desirably spaced intervals, or in a practically continuous manner without danger of two or more sheets arriving at the ruling machine at the same time, and with the attention of but a single operator.

45 It is further to be understood that, while I have shown and described my improvements particularly in connection with a ruling machine, they may be adapted with equal facility in connection with printing 50 machines, embossing machines, paper box making machines, sizing apparatus, and in fact, any machinery to which it is desired to feed sheets of paper in substantially the manner set forth, and each of the foregoing 55 references to a ruling machine is therefore to be taken as merely representative of the class of machinery to which my invention is adapted for application.

I claim:

60 1. In a paper sheet feeding machine, a blast pipe vertically adjustably mounted at one side of the paper to be fed, an air pump for supplying air to the said blast pipe, and blast nozzles adjustably mounted on the said

blast pipe for delivering air against the adjacent side of the paper stack for the purpose described. 65

2. In a paper sheet feeding machine, blast nozzles arranged at one side of the stack of paper to be fed, for directing air thereagainst to agitate the edges of the sheets of the stack, an air pump, connections between the air pump and the said nozzles for delivering air to the latter, a cut-off valve within 70 said connections, and a controlling valve also within the said connections whereby the force of blast from the said nozzles controlled by the cut-off valve may be simultaneously regulated. 75

3. In a paper sheet feeding machine, a 80 pair of concentric blast tubes, the inner tube of which is provided with a single slot, and the outer tube of which is provided with a series of spirally arranged apertures, the said tubes being rotative relative to one another 85 whereby a selected aperture of the outer tube may be registered with the slot of the inner tube, an air pump, air connections between the said pump and the said inner tube, and nozzles adjustably disposed upon the 90 outer tube for directing blasts against the paper stack, substantially as described. 95

4. In a paper sheet feeding machine, a pair of concentric blast tubes, the inner tube of which is provided with a single slot, and 95 the outer tube of which is provided with a series of spirally arranged apertures, the said tubes being rotative relative to one another whereby a selected aperture of the outer tube may be registered with the slot of the inner 100 tube, an air pump, air connections between the said pump and the said inner tube, nozzles adjustably disposed upon the outer tube for directing blasts against the paper stack, substantially as described, and connections 105 for adjusting the said concentric tubes vertically with respect to the said paper stack, substantially as described.

5. In a paper sheet feeding machine, a suction cylinder for withdrawing paper 110 from a stack, having a series of perforations, bearings in which the said cylinder is mounted to rotate, means for rotating the cylinder, a downwardly opening mouthpiece having a curved lower slotted wall engaging the inner periphery of the cylinder adjacent its 115 perforated portion, non-rotatable supports extending from the ends of the said mouthpiece, substantially axial of the said cylinder, and having vertically movable bearings 120 whereby to permit movement of the mouthpiece by gravity against the lower portion of the cylinder, one of said supports being in the form of a tube, an air pump, and connections leading from the suction side of the 125 said pump to the said tube.

6. In a paper sheet feeding machine, a suction cylinder for withdrawing paper

from a stack, having series of perforations, and a sleeve surrounding the said cylinder and adjustable lengthwise thereof to cover selected openings and regulate the effective 5 width of its said perforated section.

7. In a paper sheet feeding machine, a suction cylinder for withdrawing paper from a stack, having an intermediate perforated section, and sleeves surrounding the 10 same at opposite sides of said perforated section and adjustable upon the cylinder to cover selected openings and regulate the effective width of its perforated section.

8. In a paper sheet feeding machine, a suction cylinder for withdrawing paper from a stack, bearings in which the said cylinder is rotatably mounted, adjustable connections for rotating the said cylinder and controlling the speed of such rotation, said 20 cylinder having an intermediate annular series of perforations, a suction mouthpiece non-rotatably disposed within the said cylinder and vertically movable by gravity to engage the lower portion thereof, said mouthpiece having a longitudinal slot extending the full width of the perforated section of the cylinder, suction connections leading to the said mouthpiece, and means for regulating the effective area of the perforated section 30 of the cylinder, all as described.

9. In a paper sheet feeding machine, a feed table adapted to hold a paper stack, a suction cylinder arranged above the forward edge of the feed table to withdraw sheets 35 therefrom, blast nozzles arranged below the said suction cylinder and acting against the paper stack to agitate the paper sheets and assist the action of the suction cylinder, an air pump, connections between the said pump and the suction cylinder and blast nozzles 40 and having regulating valves, a cut-off valve in the suction cylinder connections, and means for automatically opening and closing the said cut-off valve.

45 10. In a paper feeding apparatus for ruling machines, the combination of a feed table supporting the paper to be fed, a series of feed tapes for conveying the paper to the ruling machine, automatic means for withdrawing the paper from the feed table and transferring the same to the said tapes, and means for actuating said apparatus including adjustable gears connected to the driven 50 part of the ruling machine.

55 11. In a paper feeding machine, a rotatable perforated suction cylinder for withdrawing paper from a stack, suction means therein, and means movable exteriorly thereof for cutting off selected perforations 60 and thus controlling the effective area.

12. In a paper sheet feeding machine, a rotatable suction cylinder for withdrawing paper from a stack, having a perforated section, suction means therein, and manually

operated means movable exteriorly thereof 65 for cutting off selected perforations and thus controlling the effective area.

13. In a paper sheet feeding machine, a feed table on which the paper to be fed is arranged in a stack, and means for agitating 70 the sheets at one side of the table, said means being adjustable laterally and vertically with respect to the stack and including a horizontal vertically adjustable blast pipe, and nozzles longitudinally adjustable on and 75 vertically movable with, said blast pipe.

14. In a paper sheet feeding machine, blast nozzles arranged at one side of the stack of paper to be fed for directing air thereagainst, a horizontal blast pipe on which said 80 nozzles are longitudinally adjustable, extending transversely across the forward face of the stack, an air pump, flexible connections between said pump and said blast pipe, and bearings in which said blast pipe is adjustable vertically of the paper stack to raise 85 and lower said nozzles.

15. In a paper sheet feeding machine, an upper vertically adjustable blast pipe extending transversely across the stack of paper to be fed, a lower stationary transverse blast pipe, flexible connections between the opposite ends of said blast pipes, an air pump, air connections between the said pump and the lower blast pipe, and a controlling valve located adjacent one end of 90 said lower blast pipe for controlling the force of blast communicated to the upper blast pipe, and blast nozzles arranged on and communicating with the said upper 100 blast pipe.

16. In a paper sheet feeding machine, blast nozzles arranged at one side of the stack of paper to be fed for directing air thereagainst, a blast pipe extending transversely across the forward face of the said stack, and vertically adjustable with respect thereto, air supply connections leading to said pipe, and nozzles communicating with, and adjustable longitudinally along, said 110 pipe, transversely of the said stack.

17. In a paper sheet feeding machine, a pair of concentric blast tubes extending transversely across the front side of the paper stack to be fed and adjustable vertically 115 with respect thereto, the inner tube having a single longitudinal slot and the outer tube being rotatable on the inner tube and having a series of apertures for independent registry with said slot of the inner tube, air supply connections leading to the inner tube, and nozzles disposed on, and adjustable along, said outer tube for registry with a selected aperture thereof.

18. In a paper sheet feeding machine, a 125 rotatable perforated suction cylinder for withdrawing paper from a stack, a downwardly opening suction mouth-piece extend-

ing within said cylinder adjacent its perforations, and non-rotatable supports for said mouth piece extending axially of the cylinder and including axially extending rods having vertically movable bearings at the opposite ends of the suction cylinder whereby to permit of vertical movement of said mouth piece by gravity to maintain its lower face in snug contact with the cylinder at all times.

19. In a paper sheet feeding machine, a suction cylinder, a suction mouthpiece therein capable of vertical movement, an air tube communicating at its inner end with said

mouthpiece, an air pipe below said cylinder, 15 a flexible air connection between one end of said pipe and the outer end of said tube, an air pump, connections between the suction side of said pump and the other end of said pipe, a manually controlled valve in the 20 said pipe for regulating the force of the suction, and an automatically controlled valve also in said pipe for periodically cutting off the suction to said mouthpiece.

ALBERT BROADMEYER.
